UNITED STATES PATENT OFFICE

2,575,023

FUEL RECEIVING AND CONVEYING APPARATUS

Eugene Martin, Wesleyville, Pa., assignor to Read Standard Corporation, a corporation of Delaware

Application December 11, 1946, Serial No. 715,496

1 Claim. (Cl. 198-15)

1
This invention relates to material conveying mechanism and is directed, more particularly, to an improved coal conveying unit of a locomotive stoker for application to the locomotive tender.

The current trend on many railroads is toward the elimination of fuel stops through the use of longer tenders having greater coal carrying capacity. Road clearances, tunnels, etc., limit the width and height of the tender fuel bin, so that additional coal space can only be provided by lengthening of the tender fuel bin. The conventional single screw if applied to such a fuel bin would be of such length that it would be difficult to handle and install, and in those instances where the stoker is operated without slide plates, the weight of the additional coal on the screw conveyor imposes an undesirably high load.

Various sectional screw arrangements and trough constructions have previously been suggested, as illustrated in U. S. Patent 2,029,297 to W. C. Peyton, issued February 4, 1936, for use in unusually long tender fuel bins; and it is an object of the present invention to provide an improved stoker unit of the general type shown in the Peyton patent, employing offset screw conveyors and troughs, which is simple in construction, easily installed, and sufficiently compact to readily fit between the fuel bin floor and under frame of the tender.

It is another object of the invention to provide a stoker tender unit of the above type that may be applied to a tender fuel bin dispensing with the customary slide plates, and in which at no time is it necessary for a single screw conveyor to carry the entire load.

It is another object of the invention to provide a stoker tender unit of the above type in which the drive connections for the conveyor screws are readily accessible for purpose of installation, repair or replacement.

It is another object of the invention to provide improved operating mechanism for the offset screw conveyors in a stoker tender unit of the above type, whereby the front tender screw may be operated independently of the back tender screw and when necessary, both screws may be conveniently operated together.

With these and other objects in view, the invention consists in the novel construction, arrangement and combination of parts, as will be understood from the preferred and practical embodiment of the invention hereinafter described and illustrated in the accompanying drawings, in which

2

Figure 1 is a view of the novel stoker trough in side elevation shown applied to a locomotive tender;

Figure 2 is a fragmentary enlarged plan view of an intermediate portion of the novel stoker trough shown in Figure 1.

Figure 3 is a longitudinal vertical central section through that portion of the invention illustrated in Figure 2;

10 Figure 4 is a sectional view taken on the line 4-4 of Figure 3;

Figure 5 is a sectional view taken on the line 5-5 of Figure 3; and

15 Figure 6 is a dimetric view of the rearward portion of the novel stoker trough with parts of the gear housing broken away to show the drive mechanism.

In the drawings, referring particularly to Figure 1, the letter T designates a locomotive tender and S a stoker for delivering fuel from the tender to the locomotive. The locomotive and the forward end of the stoker are not shown, since the invention resides in the tender unit of the stoker.

The tender T is provided with a frame 10 and a fuel bin 11, the latter having a floor 12 in which is formed a longitudinally elongated opening 13 extending substantially the length of the fuel bin and preferably centrally between the sides thereof to form a downwardly opening fuel discharge outlet. A stoker hopper 14 is mounted in the space between the tender frame 10 and the fuel bin floor 12 and extends longitudinally beneath the discharge outlet therein substantially the full length of the fuel bin floor, with its longitudinal axis preferably coinciding with the central longitudinal plane of the tender.

The hopper 14 is of built-up construction including a front casting 15 forming the forward end portion of the hopper, a rear casting 16 forming the rearward end portion of the hopper and the adjacent intermediate castings 17 and 18 forming an intermediate portion of the hopper. The castings 17 and 18 are rigidly secured together in a suitable manner, as by bolts 19 passing through the abutting flanges 20 and 21, as shown in Figure 2. Bent sheet metal plates 22 and 23 are suitably secured, by riveting or welding, to the castings 15 and 17, and castings 16 and 18, respectively; the plate 22 and castings 15 and 17 forming a generally U-shaped front trough 24, and the plate 23 and castings 16 and 18 forming a generally U-shaped rear trough 25.

The upper edges of the front trough 24 and rear trough 25 are preferably in the same horizontal plane, but the floor of the rear trough 25

is in a plane above the floor of the front trough 24, so that the delivery end of the rear trough 25 is offset above the receiving end of the front trough 24. The bottom of the front trough 24 preferably inclines from its receiving to its discharge end.

Fuel is conveyed through the hopper 14 by screw conveyors 26 and 27 mounted, respectively, in the troughs 24 and 25. Since the bottom wall portions of the troughs 24 and 25 are offset in planes one above the other, as previously described, and the screw conveyors 26 and 27 are mounted in the bottom of the troughs, as shown in Figure 3, it is apparent that they are similarly offset with respect to each other. Referring to Figures 2 and 3, it will be seen that the axes of the screw conveyors 26 and 27 lie in the same vertical longitudinal plane. The forward end of the rear screw conveyor 27 extends forwardly beyond the rearward end of the front screw conveyor 26 and projects into the front trough 24.

The screw conveyors 26 and 27 are driven from their rearward ends through gearing disposed in the gear housing 28, see Figure 6, which is preferably formed as part of the rear casting 16. The mechanism for driving the screw conveyors comprises a driving engine (not shown) connected with the reduction gearing in gear housing 28 through a system of connected shafts, including the drive shaft 29 which is journaled in bearing 30 formed with the rear casting 16, and a bearing (not shown) formed on the inside of the gear housing cover 31.

The drive shaft 29 is provided with a pinion 32 meshing with a reduction gear 33 which is mounted on the reduction gear shaft 34. The reduction gear shaft 34 is provided with the pinions 35 and 36 mounted, respectively, fore and aft of the reduction gear 33. Pinions 35 and 36 mesh with reduction gears 37 and 38, respectively, mounted on driven shafts 39 and 40, respectively. A coupling 41 connects the forward end of shaft 39 with the rearward end of a shaft 42 which extends forwardly beneath the rear trough 25, the torque being transmitted from the front end of shaft 42 to the rearward end of front screw conveyor 26 through connecting means, as best shown in Figure 3 and as described hereinafter.

The reduction gear 38 is loosely mounted on the shaft 40, the rear portion of the shaft 40 being splined as at 43 to accommodate a sliding clutch 44. The clutch 44 is provided with projecting lugs or teeth 45 adapted to cooperatively engage complementary projecting teeth 46 formed on the gear 38. For operating the clutch 44 there is provided a rock shaft 47 journaled in the gear housing cover 31 upon which is rigidly mounted a yoke or bifurcated member 48. Each fork of bifurcated member 48 is provided in its free end with a recess 49 adapted to receive a pin or lug 50 projecting outwardly from a split collar 51 of the clutch 44.

The clutch is operated by means of a clutch operating handle 52 at the front of the tender, movement of the handle being transmitted to the clutch operating lever 53 through the clutch operating rod 54. When the rod 54 is pulled forward the collar 51, by reason of its connection with the bifurcated member 48, will move the clutch 44 in engagement with the gear 38, whereby rotating movement is transmitted to the shaft 40 and thence to rear screw conveyor 27 with which it is operatively connected. By disengaging the clutch 44, the rear screw conveyor 27 will

remain idle while the front screw conveyor 26 continues to operate.

At its forward end, the rear screw conveyor 27 is journaled in a bearing 54 pendently supported by the T-shaped bearing support 55, the ends of the arms of the T-shaped bearing support 55 being rigidly secured, in any suitable manner, to the upper side walls of the front trough sheet 22, all as best shown in Figures 2, 3 and 4.

Referring particularly to Figures 2, 3 and 5, the casting 18, which forms the forward portion of the rear trough section 25, is provided adjacent the forward end of its trough-shaped bottom with a rectangular opening 56. Longitudinally extending flanges 57 and 58 depend from the trough-shaped portion of the casting 18 along the sides thereof defining the rectangular opening 56. The inner side walls of the flanges 57 and 58 are provided with the longitudinally extending horizontal guideways 59 and 60, respectively, arranged to receive the flanged guides 61 and 62, respectively of the cover plate 63, as best shown in Figure 5.

The cover plate 63 is concave in transverse cross section and when in place it completes, with the upper side walls of the casting 18, a trough-like structure. A plurality of bolts 64 secure the cover plate 63 in position. On removing the bolts 64, the cover plate 63 may be slid forward without disengaging or removing the screw conveyors 26 and 27, to expose the opening 56, thereby providing ready access to the driving connection between the shaft 42 and front screw conveyor 26.

A pedestal 65, preferably formed as an integral part of the casting 18, supports the trough-shaped portion of casting 18 on the tender under-frame 10.

The casting 17, which forms the rearward portion of the front trough section 24, is provided with an upstanding rear wall 66, as best shown in Figures 3 and 4. The rear wall 66 is formed with an opening registering substantially with the open forward end of the trough-shaped portion of casting 18, providing communication between the rearward trough section 25 and the forward trough section 24 for the passage of coal from the former to the latter.

In order to drive the inclined front screw conveyor 26 from the horizontal shaft 42, a flexible drive connection is employed. The drive connection includes a coupling shaft 67 which is journaled in a bearing 68 formed with the rear wall 66 of casting 17. The coupling shaft 67 is provided with a forwardly extending polygonal extension 69 entering a corresponding polygonal socket in the rearward end of the screw conveyor 26, providing a drive connection between the coupling shaft 67 and screw conveyor 26. Bolts 70, carried by the screw conveyor 26 pass loosely through the polygonal extension 69 providing for slight relative longitudinal movement between the screw conveyor 26 and coupling shaft 67 but preventing disengagement of one from the other.

Rearward thrust of the screw conveyor 26, incident to its forward conveyance of coal, is transmitted to the bearing 68 by a thrust washer 71 mounted to rotate with the coupling shaft 67 and a thrust washer 72 loosely mounted on shaft 67. A collar 73 secured by a bolt 74 on the coupling shaft 67 immediately rearward of the bearing 68, transmits to the bearing 68 the forward thrust of the screw conveyor 26 incident to reverse operation thereof.

The shaft 42 is mounted near its forward end

in a bearing 75 which is secured, in any suitable manner, to the pedestal portion 65 of the casting 18 subjacent the rearward end of the opening 56 in the bottom of the trough-shaped portion of casting 18. The adjacent ends of shaft 42 and coupling shaft 67 are provided, respectively, with polygonal extensions 76 and 77 on which are mounted, respectively coupling members 78 and 79 of a flexible coupling. The coupling members 78 and 79 have a polygonal bore, arranged to receive the polygonal shaft extensions 76 and 77, respectively, providing a drive connection between each shaft extension and its respective coupling member, while at the same time permitting relative longitudinal movement between each shaft extension and its respective coupling member.

The adjacent ends of coupling members 78 and 79 are provided with loosely interfitted tongues, as best shown in Figures 3 and 5, the coupling member 78 having diametrically opposite tongues 80 and 81, and the coupling member 79 having diametrically opposite tongues 82 and 83. The interfitted tongues 80, 81, 82 and 83 provide for transmission of torque from one coupling member to the other, while the loose fit of the tongues provide a flexible drive connection between the horizontal shaft 42 and the inclined coupling shaft 67 and screw conveyor 26. A spring 84 under compression and mounted within the interfitted tongues normally limits the depth of engagement of the tongues, to eliminate binding between the coupling members when in operation.

It is evident from the above description that the flexible drive connection between shaft 42 and front screw conveyor 26 is outside the passage of the coal through the hopper 14 and therefore free of interference, and is readily accessible through opening 56 of the trough shaped portion of casting 18 upon sliding the cover plate 63 forward.

In order to remove the parts of the flexible coupling or the coupling shaft 67 for purpose of replacement or repair, the bolt 74 holding the collar 73 on the coupling shaft 67 can be removed through the opening 56 upon sliding the cover

plate 63 forward. The bolts 70 securing the front screw conveyor 26 and coupling shaft 67 can be removed, the screw conveyor 26 pulled forward, and then the coupling shaft 67 can be pulled forward, thereby freeing the parts of the flexible coupling.

I claim:

A stoker trough adapted to be mounted throughout its length beneath the fuel bin of a locomotive tender, said trough comprising a rearward open mouth trough section and a forward open mouth trough section in end to end communication, both said sections being disposed to receive fuel by gravity from said fuel bin, the bottom wall of said rearward trough section being offset in a plane above the bottom wall of said forward trough section at the adjacent ends of said trough sections, a connecting wall joining the adjacent ends of said rearward and forward trough section bottom walls, a recess formed in the forward end of the bottom wall of said rearward trough section extending rearward of said connecting wall, longitudinally extending guideways formed in that portion of said rearward trough section defining the sides of said recess, and a plate slidably mounted in said guideways normally closing said recess and forming part of the bottom wall of said rearward trough section, said plate being movable forwardly out of said recess into said forward trough section to provide access from within the trough to the space therebeneath through said recess.

EUGENE MARTIN.
